UNITED STATES PATENT OFFICE.

JAMES BURKE, OF ERIE, PENNSYLVANIA, ASSIGNOR TO BURKE ELECTRIC COMPANY, A CORPORATION OF PENNSYLVANIA.

DYNAMO-ELECTRIC MACHINE.

No. 803,979.

Specification of Letters Patent.

Patented July 21, 1908.

Application filed February 4, 1907. Serial No. 355,564.

To all whom it may concern:

Be it known that I, JAMES BURKE, a citizen of the United States, residing at Erie, in the county of Erie and State of Pennsylvania, 5 have invented certain new and useful Improvements in Dynamo-Electric Machines, of which the following is a full, clear, and exact specification.

My invention relates to dynamo electric 10 machines and particularly to a method of and means for generating current for supplying a three wire direct current system of distribution.

The advantages of three wire distribution 15 have been heretofore considerably offset by the large first cost of the generating apparatus, and this has involved a plurality of generating machines or a single generating machine together with expensive auxiliary 20 apparatus.

The object of my invention is to reduce the generating apparatus to a simple and inexpensive construction, and to embody the same in a single generating machine.

25 In order to adapt a direct current machine for a three wire system, it has been proposed to connect the neutral wire to brushes which make contact with the commutator segments midway between the segments which are in 30 engagement with the positive and negative brushes. This method is decidedly objectionable in practice, particularly when the mains are unbalanced.

In the operation of a dynamo of usual 35 form, any one point in the armature winding changes gradually from the potential of the positive brush to the potential of the negative brush approximately and vice versa continually, and there is no point which remains 40 constantly at a fixed potential.

In carrying my invention into practice, I introduce means for maintaining a point at constant potential within practical limits, and I accomplish this directly by means of 45 generating windings or coils added to a direct current machine and without the use of other auxiliary apparatus, such as transformers or coils of high self-induction. The additional generating windings or coils are preferably 50 in electrical connection with the armature of the direct current machine and wound upon the same core. The additional generating windings maintain one terminal of each of said windings at a fixed potential, 55 and as the machine rotates, the other termi-

nals of said windings vary in potential and the electromotive force generated by these windings is just sufficient in amount at each instant to maintain the relation desired.

My invention will be understood by reference to the accompanying drawings and following description.

Figures 1 and 2 are diagrams for explaining my invention; Figs. 3 to 7 are diagrams showing various embodiments of my invention; Fig. 8 is a diagram showing my invention applied to a multipolar machine having a drum wound armature; Fig. 9 is a sectional view showing the position of the conductors of Fig. 8 on the armature; and Figs. 10 and 70 11 are diagrams showing my invention applied to a five wire system of distribution and to the control of a variable speed motor.

In explaining the theory of my invention, and in order to understand the practical embodiments, I will first consider Fig. 1, in which the armature coils of a direct current machine are indicated at 1 and are connected to the commutator bars 2. The machine is indicated as bi-polar having the poles 3 and 75 positive and negative brushes 4. In addition to the usual main winding, there are provided additional generating windings or coils 5^a, 5^b, 5^c wound upon the same core as winding 1, one end of each of these three windings 80 being connected to the collector ring 6. The remaining ends of the windings are connected to points a, b, c, in the armature, which points in this example are 120 electrical degrees apart. The auxiliary windings or coils are shown as connected to the commutator segments, but they may, if desired, be connected to points in the armature winding itself. The positive and negative mains of the three-wire system are indicated at 7, 8 and the 90 neutral wire at 9. The mains 7, 8 are connected to the positive and negative brushes 4 and the neutral wire is connected to a brush 10 bearing on the collector ring 6.

In order to maintain the neutral wire at a 100 fixed potential with reference to the potentials of the positive and negative mains and so secure a three wire distributing system, the ends of the windings 5^a, 5^b, 5^c being connected to ring 6 and thus to the neutral wire 105 must also be maintained at a fixed potential with reference to that of said mains. In these windings there is generated an alternating electromotive force, but the electromotive force generated in each one at any 110

instant, although different from that generated in the others, is always such in each winding that the potential of ring 6 remains unchanged, whereas the potentials of the ends of the windings connected to points in the armature are continually changing from positive to negative and from negative to positive with reference to the potential of the neutral.

10 It is understood of course, that the potential around the commutator or around the winding 1, gradually falls from the positive to the negative brush and therefore the potential of *a*, which is shown midway between the positive and negative brushes, is approximately half-way between the potential of the positive and negative mains, or in other words is the same as that of the neutral or the same as the desired potential of the neutral. Therefore since the winding 5^a is connected to the neutral through the collector ring 6 at one end and to point *a* at the other, then in order that the neutral should be at the same potential as point *a* as desired, the winding 5^a should be in such position at this instant that it will generate no electromotive force or no resultant electromotive force. The potential of point *b* is between that of the negative main and that of the neutral and is approaching the potential of the neutral assuming that the direction of rotation is that indicated by the arrow. As winding 5^b is connected between point *b* and the neutral, then in order to maintain the neutral at the desired potential, the winding 5^b must be so located as to generate an electromotive force equal to the difference in potential between that of point *b* and the desired potential of the neutral. Winding 5^b is therefore indicated in a position to generate an electromotive force equal to the difference in potential between point *b* and the neutral; and as the potential of point *b* is approaching the potential of the neutral at the instant represented, winding 5^b is represented in such position with reference to the magnetic field that it is generating a gradually decreasing electromotive force with reference to the direction of rotation indicated by the arrow. The potential of point *c* is above that of the neutral and between the neutral and positive brush, and is approaching that of the positive brush. Winding 5^c is therefore diagrammatically indicated in such a position that it is generating an electromotive force equal to the difference between the potential of the neutral and that of point *c* and generating an electromotive force opposite in direction to that of winding 5^b. It is also generating an increasing electromotive force so as to balance the increasing potential of point *c*. Consequently, the instantaneous electromotive force generated by each of the windings 5^a, 5^b, 5^c is equal to the potential difference be-

tween the neutral and the points in the armature to which the respective windings are connected. Moreover, as the armature rotates and the potential of points *a*, *b*, *c* continuously changes with reference to the desired constant potential of the neutral point, the electromotive force generated in each winding 5^a, 5^b, 5^c changes in the same way and to the same degree; consequently the potential of collector ring 6 remains fixed 75 and always mid-way between that of the positive and negative brushes, and the desired potential of the three-wire main is obtained. It will be seen therefore that the windings 5^a, 5^b, 5^c act to generate alternating 80 current electromotive forces which balance the changing potentials of the points in the main windings to which they are connected and so maintain the potential of the neutral constant. When the load on the system is unbalanced, current will flow either to or from ring 6 through the neutral wire and will pass through the generating windings 5^a, 5^b, 5^c to or from the armature winding 1. The windings 5^a, 5^b, 5^c therefore not only serve 85 as means for maintaining the neutral at fixed potential by their action as generating windings, but also serve as a path for the current due to an unbalanced load. It will be noted that the maximum electromotive force generated by each winding 5^a, 5^b, 5^c in one direction is equal to one-half the electromotive force between the positive and negative brushes under perfect conditions, and preferably is made as nearly so as possible in practice. This will be understood since the electromotive force generated by each winding must at some time equal the full electromotive force between the neutral and any one of the brushes, and this electromotive force is 95 equal to one-half of the electromotive force between positive and negative brushes. That is, the number of conductors or turns per each alternating current winding or auxiliary winding 5^a, 5^b, 5^c, etc., should be equal to, or equivalent to, one-half of the number of conductors or turns per circuit from brush to brush of the main armature winding having the commutator.

I may in some cases provide a greater or less number of generating windings than three.

Fig. 2 illustrates a form in which only two windings 5^a, 5^b, are used. These windings are displaced approximately 90 degrees electrically and are connected to points in the main armature winding approximately 90 electrical degrees apart. In the position shown and at that instant, winding 5^a is connected to a point in the main winding midway between the positive and negative brushes, which point is consequently of the same potential as the neutral and therefore winding 5^a should and does generate no electromotive force being shown in the neutral 130

position. Winding 5^b is shown connected to a point which at the instant considered, is at the same potential as the negative brush and should therefore generate its maximum electromotive force, and is shown diagrammatically in position for generating maximum electromotive force. As the armature rotates, the windings 5^a, 5^b will at all times cooperate to maintain the neutral potential.

10 Only one auxiliary generating winding, as 5^a, may be used, but better results are obtained by the use of more than one auxiliary winding, particularly where the system is likely to be very much unbalanced.

15 From the preceding, the general theory upon which my invention is based will be understood, and which theory is fundamentally based upon generating in one or more auxiliary windings by dynamic action variable electromotive forces for maintaining a fixed potential between the potentials of the outside mains. I will now consider a few practical embodiments of this general theory and of my invention.

20 Fig. 3, shows a bi-polar machine having an armature winding of the Gramme type, the ring core being indicated at 11, and the main winding 12 is shown as having a total of 32 conductors or turns. As the machine is bi-

25 polar and has two brushes, there are two circuits from brush to brush, giving 16 conductors per circuit of the main winding. The winding is also shown as having two conductors per coil between commutator segments;

30 and these coils of two conductors each are indicated as displaced 22.5 electrical degrees from each other, and the two conductors of each coil are located in the same phase substantially, being shown in the same slot. It

35 is apparent that the total electromotive force generated in each of the two circuits of the main winding is produced by the united effect of the eight coils per circuit, and that some of these coils are generating a high electromotive force while others, being in different phase position with reference to the magnetic field, are generating less electromotive force. The total electromotive force is therefore made up of the united effect of

40 eight coils, each in a different phase and some of which are subjected to a magnetic field very much different in strength from that of the others. Moreover, the irregularity of the magnetic field causes corresponding variation in the electromotive forces generated by the different coils.

45 In locating the auxiliary winding for maintaining the neutral potential, the irregularity of the magnetic field, and of the electromotive forces generated in the main winding, must be considered when such conditions exist, as is the case in all commercial types of machines at the present time; and for the purpose of balancing the main winding, the auxiliary winding must be so related thereto that for

each phase of the main winding, there is a substantially corresponding location of part of the auxiliary winding. In other words, the auxiliary winding must be distributed so that its parts will be subjected to conditions similar or substantially similar to that of the parts of the main winding and so compensate for every variation in the magnetic field to which the parts of the main winding are subjected. If the auxiliary winding be so located or distributed, then the same variations to which the main winding is subjected, and which thereby determine the electromotive force generated by the main winding will correspondingly affect the auxiliary winding and a corresponding compensation will be secured. Thus, referring to Fig. 3, we may consider the circuit of the main winding from negative to positive brush which is on the upper half of the core and designated by the character 12. This consists of eight coils of two conductors per coil in phases marked 22.5 degrees, 45, . . . to 180 degrees, respectively. The auxiliary winding 13 consists of one-half that number of conductors and comprises 90 eight conductors in series having one conductor in each of the phases 22.5, 45, . . . to 180 degrees, one conductor being in each of the slots in which the two conductors of the main winding are located. One terminal of the auxiliary winding is connected at 14 to the lead of the main winding which is connected directly to the positive brush at the position shown, and the other terminal of the auxiliary winding is connected to the collector ring 6. At the position represented, it is apparent that the auxiliary winding must generate an electromotive force equal to one-half that between the positive and negative brushes in order to obtain the desired potential for the neutral, since one end of the auxiliary winding is substantially at the same potential as the positive brush. The electromotive force generated by the auxiliary winding must therefore be one-half that generated by the main winding, and this will be the maximum electromotive force generated by the auxiliary winding.

It is apparent that for each phase of the coils of two conductors of the main winding 12, there is one conductor in the auxiliary winding in the same phase. Consequently in each of these phases the auxiliary winding will generate one-half of the electromotive force generated by the main winding. The potential of the ring 6 and of the neutral must therefore be half way between the potentials of the positive and negative brushes. The desired potential of the neutral will also be maintained at other positions of the armature, since the changing phases and electromotive forces of the conductors of the main winding are always balanced or correspondingly reproduced in the conductors of the auxiliary winding. For example, consider

Fig. 4 in which the armature is shown as having rotated 45 degrees from the position of Fig. 3. As the potential of the neutral is half way between the positive and negative brushes, then since the potential of point 14 is reduced in the position of Fig. 4 by the amount of electromotive force generated by the two coils of the main winding in the phases 202.5 and 225, and since the potential of the opposite point 15 is reduced a similar amount, it follows that the potential of the neutral must also be half way between the potentials of points 14 and 15. As the difference of potential between points 14 and 15 is the resultant electromotive force of coils of the main winding in phases marked 67.5, 90, etc., to 225 degrees inclusive, and as the auxiliary winding generates one-half of the electromotive force generated in such coils of the main winding, and is connected to point 14, it follows that the potential of ring 6 will be maintained at a potential half way between the potentials of points 14 and 15, that is, at the desired potential of the neutral. Or if we consider it from another point of view, it is clear that the potential of point 14, which in Fig. 3 was at the potential of positive brush 4, is reduced in the position of Fig. 4 and is nearer the potential of the neutral by the amount of the electromotive force generated in coils of the main winding at 202.5 and 225. Consequently, the total electromotive in the auxiliary winding should be reduced by the amount of electromotive force generated in said two coils in order to maintain the neutral at the same desired fixed potential. Referring to Fig. 4, it will be seen that the electromotive force is thus reduced because the two conductors of the auxiliary winding now in positions 202.5 and 225 degrees generate counter-electromotive forces and the conductors of the auxiliary winding generating electromotive forces in the opposite direction are now reduced by the two conductors of the auxiliary winding which in the position of Fig. 3, were at phases 22.5 and 45. This reduced electromotive force and the counter-electromotive force produce a resultant decrease in the electromotive force of the auxiliary winding by an amount equal to the electromotive force generated by the two coils of the main winding at positions 202.5 and 225 above mentioned. The potential of the neutral will therefore remain fixed. It will be apparent that for every other position of the armature, a proper balance will be secured and the potential of the neutral remain fixed.

Instead of placing the conductors of the auxiliary winding in the position shown in Fig. 3 and 4, relatively to the main winding, the auxiliary winding may be arranged as in Fig. 5 upon the principle that any conductor of an auxiliary winding may be shifted 180 electrical degrees and so be placed in a corre-

sponding position under a pole of opposite polarity, provided the direction of the conductor is changed so that the electromotive force generated will have the same effect in the auxiliary winding. For example, in Fig. 5 the conductors of the auxiliary winding in positions 180, 157.5, 135 and 112.5 are the same as in Fig. 3, but the remaining conductors are shifted 180 degrees from the position of Fig. 3, the auxiliary conductor at 270 degrees of Fig. 5 corresponding to that at 90 degrees of Fig. 3, that at 247.5 corresponding to that at 67.5, that at 225 corresponding to that at 45, and that at 202.5 corresponding to that at 22.5. Also the direction of the four conductors transposed in Fig. 5 is opposite to the corresponding conductors of Fig. 3, in order to preserve the desired action. This transposition of conductors will be understood to be correct from the fact that the result is the same in the auxiliary winding whether the conductor is moving in one field at a certain position or in the opposite field of corresponding position with its direction reversed. The application of this feature of my invention is important in tending to secure equal electrical and mechanical effects, that is, in tending to avoid unequal distortion of magnetic field when current flows in the auxiliary winding and in tending to maintain a mechanically symmetrical and balanced armature. For example, in Fig. 6, the winding will have the general effect of that of Fig. 3 and on account of the more symmetrical distribution of the auxiliary winding, the armature will be more nearly mechanically balanced and the electrical conditions become more uniform. In this figure the eight conductors of the auxiliary winding are not all on one half of the armature as in Fig. 3 and Fig. 5, but the conductors of the auxiliary winding of Fig. 3 in phases marked 22.5, 67.5, 112.5, and 157.5 are transposed to the other half of the core in Fig. 6, 180 degrees from the position in Fig. 3 and the direction is opposite as explained with reference to Fig. 5. The desired operation will consequently be secured, and at the same time secure a more symmetrical condition. Referring to Fig. 6, it will also be seen that the sequence of connection of the conductors of the auxiliary winding is not the same as in Fig. 3, and that in Fig. 6, the conductors are connected in succession around the ring which allows the connections to be simplified over what would otherwise be necessary. The same resultant electromotive force will be secured however, regardless of the sequence of connection so long as the location of the conductors and the direction of electromotive forces generated are correct.

Fig. 7 shows the same form of machine and windings as in Fig. 3, but in Fig. 7 there is an additional auxiliary winding 16 connected to

the point 17 of the main winding 90 degrees from point 14 to which the auxiliary winding 12 is connected. Starting from point 17, the auxiliary winding 16 is similar in the first four turns to the winding 13 but instead of continuing and overlapping winding 13, the remaining four conductors are transposed 180 degrees and connected as explained with reference to Fig. 5. With this construction, it will be seen that the conductors are symmetrically located throughout the armature giving the desirable advantages of such an arrangement. Also with two windings, the balancing effect will be improved as already stated. With two auxiliary windings it is preferable to connect them to points in the main winding substantially 90 electrical degrees apart, but they may be connected to points widely different from 90 degrees displacement if desired. In each case however, the auxiliary winding should have its conductors so located and connected as to balance or correspond to the conductors per circuit of the main winding beginning at the point of the main winding at which the auxiliary winding is connected. That is, in Fig. 7 for example, the auxiliary winding 16 is connected to the main winding at point 17 and the eight conductors of the auxiliary winding must correspond in their effect to the effect of the number of conductors per circuit of the main winding and beginning at point 17; that is, must correspond to the 16 conductors per circuit of the main winding in the eight phases marked 270, 247.5, 225, 202.5, 180, 157.5, 135 and 112.5. This will be better understood perhaps by considering that when point 17 is at or nearest to the potential of either positive or negative brush, the conductors of the main winding from point 17 will be generating the total electromotive force and the conductors of the corresponding auxiliary winding should therefore also be generating their highest or total electromotive force.

If three auxiliary windings are used, the points of connection in the main winding are preferably substantially 120 electrical degrees apart; if six auxiliary windings are used they are connected preferably to points substantially 60 electrical degrees apart, but the points of connection may differ widely from these displacements and may be irregularly displaced if desired provided that the auxiliary conductors are correspondingly located as above explained. Usually the stated displacements will be preferable, but very satisfactory results may be produced with other displacements.

The connections of the auxiliary winding to the main winding may be made to the commutator bars if desired, or to the end connections of the conductors of the main winding.

Although the best results will be secured by the arrangement of auxiliary conductors

as described generally with reference to Figs. 3 to 7, it will be understood that such an arrangement is not absolutely required provided the divergence is not so great as to produce a commercially impractical machine. For example, instead of locating the auxiliary conductors in the same phase positions as the corresponding main conductors, they or some of them may be located in slightly different phase positions. However, the greater the displacement from proper position and provided this displacement is not properly compensated for, the more will be the generation of unbalanced electromotive-forces and the greater the flow of useless and harmful local currents. Also, it is apparent that if the number of conductors in the auxiliary windings is not made exactly the same as described with reference to Figs. 3 to 7, the number may be slightly different and still obtain operation which may be sufficiently satisfactory, although not so satisfactory as might be secured with the best possible arrangement. For example, if the number of auxiliary conductors were very large, there might be a slightly different number employed from that theoretically required, or the phase location might be slightly different without rendering the machine useless. In all cases however, the substantial requirements for good balancing effect must be present in order to produce a commercially practical machine.

It will be understood that the auxiliary windings may be considered as connected in parallel with part of the main winding, and the auxiliary windings may therefore act to generate current in parallel therewith. By adding a large number of auxiliary windings and by making their resistance low, they may be made to carry a considerable portion of the current compared with that in the main winding. This will be so since the main winding, together with the auxiliary windings generate electromotive forces in parallel with each other and the current that will be caused to flow in the parallel circuits will be influenced by their relative resistances.

I have described my invention as applied to a bi-polar machine and to a Gramme winding as it is then in its simplest form and more easily understood. It may likewise be applied to multi-polar machines and to machines having the various forms of drum windings.

Fig. 8 illustrates as one example, a multi-polar machine having a drum winding and having my invention embodied therein. The four poles of the machine are indicated in dotted lines and designated by the characters N, S; within the poles is shown a development of the main winding and of the two auxiliary windings which are used in this instance. The commutator is indicated within the windings at 2, and the brushes 4 which

engage the commutator are shown as bearing upon the inner surface of the commutator for the sake of clearness. The two positive brushes are shown connected together and the two negative brushes are joined together as is usual in multi-polar multiple circuit windings. The collector ring is shown at 6 having one terminal of each of the auxiliary windings connected thereto. The brush 10 shown as engaging ring 6, will, of course, be connected to the neutral of the three-wire distributing mains, and the pairs of positive and negative brushes bearing upon the commutator will be connected to the outside 15 mains of the three-wire distributing mains. The conductors of the main winding are numbered consecutively from 1 to 32 inclusive. The phase positions of the conductors are designated for the purpose of reference by 20 designation of the number of electrical degrees beginning with zero degrees for conductors 1, 32. Passing from this position towards the right and coming to the lower conductors 16, 17 the number of electrical degrees 25 passed has been 360, and similarly there are 360 degrees in passing from the lower conductors back to the upper conductors. It will, of course, be understood that conductors in a certain phase position with reference 30 to a field pole of one polarity are in the same phase position as conductors located under another pole of the same polarity and in corresponding position with reference thereto. For example, conductors 4, 5 are in the 35 same phase as conductors 20, 21. Although in Fig. 8, there are shown two conductors of the main winding displaced by a small amount from each other, it will be understood that they are intended to be in the 40 same slot of the armature core and in substantially the same phase position.

As there are 32 conductors in the main winding, and as there are four multiple circuits, being a four-pole machine, there are 45 eight conductors per circuit from brush to brush bearing on the commutator. Each of the auxiliary windings consists of four conductors. One of the auxiliary windings is shown as having one terminal connected to 50 the commutator bar to which conductor 1 of the main winding is connected and comprises conductors 18^a, 18^b, 18^c and 18^d, being connected to the collector ring 6 at the other terminal. As there are points of equi- 55 potential in multi-polar machines every 360 electrical degrees apart, the auxiliary winding should be connected at one terminal to each of the points of the same potential in order to improve the balancing effect. Con- 60 sequently, in this figure there is a cross connection 19 from the beginning of the auxiliary winding, or from the commutator bar to which it is connected, to the commutator bar 360 electrical degrees therefrom. The other 65 auxiliary winding is connected at one termi-

nal to the commutator bar to which conductor 5 is connected, being also cross connected by connection 21 to the commutator bar 360 degrees therefrom, and comprises four conductors 20^a, 20^b, 20^c and 20^d. It will be noted that the points in the main winding to which the two auxiliary windings are connected, are displaced 90 electrical degrees. It will also be noted that the conductors of the auxiliary windings are so located as to secure a balanced armature, there being a conductor of an auxiliary winding diametrically opposite another in every case. It will be understood from the diagram that the auxiliary conductors are intended to be located in the same slot of the core as the two adjacent conductors of the main winding. It will also be noted that in each circuit of the main winding there is only one conductor per slot instead of two as was the case in Figs. 3 to 7. Bearing in mind the principles already explained with reference to Figs. 3 to 7, we may now understand the arrangement of the windings in Fig. 8.

Since the auxiliary winding 18 is connected to the commutator bar to which conductors 1 and 6, of the main winding are connected, the auxiliary winding must have conductors located and connected to correspond with the circuits of the main winding beginning with conductors 1 and 6. The circuit of the main winding beginning with conductor 1 comprises the following eight conductors:—1, 8, 3, 10, 5, 12, 7, and 14. Of this circuit, conductors 1 and 8 are displaced 180 degrees, and as conductor 1 passes out from the commutator end of the armature and conductor 8 returns to the commutator end, the resultant effect of each as far as generation of electromotive force is concerned, is the same. These two conductors may therefore have a single auxiliary conductor corresponding thereto and so generate a corresponding one-half electromotive force provided the auxiliary conductor is located in either of the 0 degree positions or 180 degree positions, and if in the 0 position it must be an outgoing conductor from the commutator end and if in the 180 degree position must be an incoming conductor towards the commutator end. Referring to the winding, it is found that conductor 18^d of the auxiliary winding is located in one of the 180 degree positions and is so connected in the auxiliary winding as to be an incoming conductor towards the commutator end. Conductors 1 and 8 of the main winding will therefore be properly compensated for by conductor 18^d. Taking the conductors 3 and 10 of this circuit of the main winding in the same way, it will be seen that these conductors being displaced 180 degrees, will be balanced either by an outgoing conductor in either of the 45 degree positions, or by an incoming conductor in either of the 225 degree 120 125 130 135 140 145 150 155 160 165 170 175 180 185 190 195 200 205 210 215 220 225 230 235 240 245 positions. The conductor 18^a of the auxiliary winding is located in one of the 45 degree positions and is connected in the auxiliary winding so as to be an outgoing conductor, and will therefore properly correspond to the conductors 3 and 10. Taking the next conductors 5 and 12 of this main circuit, these may be compensated for by an outgoing conductor in either of the 90 degree positions, or by an incoming conductor in either of the 270 degree positions. The conductor 18^b of the auxiliary winding is in one of the 270 degree positions and is an incoming conductor, and therefore properly corresponds in phase and direction to the conductors 5 and 12 of the main winding. The remaining conductors 7 and 14 of this circuit of the main winding may be compensated for by a conductor of the auxiliary winding which may be outgoing in either of the 135 degree positions or incoming in either of the 315 degree positions. Conductor 18^c of the auxiliary winding is an outgoing conductor in one of the 135 degree positions and is therefore suitable. It is therefore apparent that the auxiliary winding 18 comprises the proper number of conductors, and that they are located in phase positions corresponding to the phase positions of the conductors of the circuit of the main winding which is to be balanced, and it is also apparent that the conductors of the auxiliary winding are connected in such relation as to be correct in direction with reference to the phase in which they are located. The other circuit of the main winding which begins at the commutator segments to which the auxiliary winding 18 is connected, comprises the eight conductors 6, 31, 4, 29, 2, 27, 32 and 25. If we should consider in detail the phase locations of these conductors and the conductors of the auxiliary winding 18, it would be found that the conductors of this auxiliary winding would correspond in phase location and in direction to such conductors of the main winding.

Since the auxiliary winding 18 is cross connected by connection 19 to the segment of the commutator to which conductors 22 and 17 are connected, this auxiliary winding should also correspond to the two circuits of the main winding beginning with either conductor 22 or 17. If we take for illustration the circuit beginning with conductor 22, it will be seen that this circuit comprises the eight conductors 22, 15, 20, 13, 18, 11, 16 and 9. Of these conductors, 22 and 15 are displaced 180 degrees, 22 being an outgoing conductor and in phase 135 degrees, and 15 being an incoming conductor and in phase 315 degrees. The effect is consequently the same as two outgoing conductors in phase 135 degrees, or two incoming conductors in phase 315 degrees, and consequently these conductors may be compensated for by either an outgoing conductor in phase 135 degrees, or an incoming conductor in phase 315 degrees. The conductor 18^c of winding 18 is an outgoing conductor in phase 135 degrees and therefore compensates for the said two conductors of the main winding. Similarly, conductors 20 and 13 may be compensated for by an outgoing conductor in either of the 90 degree phase positions, or by an incoming conductor in either of the 270 degree positions, and this requirement is fulfilled by conductor 18^b which is an incoming conductor in one of the 270 degree positions. In the same way conductors 18 and 11 of the main armature circuit may be compensated for either by an outgoing conductor in one of the 45 degree positions or by an incoming conductor in one of the 225 degree positions, and this requirement is answered by conductor 18^a which is an outgoing conductor in one of the 45 degree positions. Also conductors 16 and 9 of the main circuit may be compensated for by an outgoing conductor in one of the 0 degree positions, or by an incoming conductor in one of the 180 degree positions. Conductor 18^a of the auxiliary winding is an incoming conductor in a 180 degree position and therefore properly corresponds to the location of conductors 16 and 9. The auxiliary winding 18 therefore is correct in location and connections for balancing the main circuit just referred to as well as the main circuits beginning with conductors 1 and 6, as above explained.

We may now consider the auxiliary winding 20 which is made up of conductors 20^a, 20^b, 20^c and 20^d. One of the main circuits compensated for by this winding will be considered in detail as an example and from the foregoing it will be understood that other circuits will be similarly compensated. One of these circuits beginning at the commutator bar through which winding 20 is connected, is the circuit comprising the conductors 5, 12, 7, 14, 9, 16, 11 and 18. Conductor 5 is an outgoing conductor in phase 90 degrees and conductor 12 is an incoming conductor in phase 270 degrees, and these conductors will be compensated for by an outgoing conductor in one of the 90 degree positions, or by an incoming conductor in one of the 270 degree positions. This requirement is fulfilled by conductor 20^b which is an incoming conductor in one of the 270 phase positions. Conductors 7 and 14 should have in the auxiliary winding either an outgoing conductor in one of the 135 degree positions, or an incoming conductor in one of the 315 degree positions. Conductor 20^a is an outgoing conductor in one of the 135 degree positions, and therefore answers the purpose. Conductors 9 and 16 should be compensated for by an outgoing conductor in one of the 180 degree positions or an incoming conductor in one of the 0 degree positions. Conductor 13^c

20^c answers this requirement, being an outgoing conductor in one of the 180 degree positions. Conductors 11 and 18 of the main winding may be compensated for by an outgoing conductor of the auxiliary winding in either of the 225 degree positions or by an incoming conductor in either of the 45 degree positions. Conductor 20^d is an incoming conductor in one of the 45 degree positions and therefore fulfills the requirement. Consequently, the circuit of the main winding beginning with conductor 5 will be properly balanced by the conductors in the auxiliary winding, since they are in proper corresponding phase positions and so connected as to be correct in direction.

From the above it will be understood that any desired number of additional auxiliary windings may be added to the structure represented in Fig. 8, and connected at any desired point in the main winding provided they are suitably located and connected. It will also be understood that the conductors of the auxiliary winding 18, or of the winding 20, may be otherwise arranged since each conductor of such windings may be placed in any one of four positions. The arrangement shown is a desirable one however, since the armature is well balanced and quite symmetrical. Of the two auxiliary windings represented in Fig. 8, it will be noted that the winding 18 has one conductor located under the influence of each of the four poles, whereas winding 20 has all of its conductors located within the range of 405 electrical degrees and nearly confined within the influence of two of the field poles. This illustrates how differently the conductors of the auxiliary winding may be located.

From the foregoing it will be understood that my invention may be applied to machines having a larger number of poles and to various other forms of armature windings. It will also be understood that my invention may be applied to machines having stationary armatures and revolving fields instead of machines having rotating armatures as above described.

Fig. 9 is a diagram which shows the location of the conductors of Fig. 8 on the armature. The poles N, S are indicated in full lines, and the armature core is designated by the character 22 and is represented in section. The core is indicated as being a slotted core, and the conductors of the main and auxiliary windings are designated by the same characters as in Fig. 8. It will be noted that the conductors of the auxiliary windings are shown as located in the bottom 60 of the slots and this location is preferable.

When it is desired to secure a multiple voltage distributing system having more than three wires, I may combine two of my three wire machines and secure a five wire system of distribution. Such a distributing

system is illustrated in Fig. 10. Two of my machines are indicated at 23 and 24, machine 23 having its positive and negative brushes, and brush bearing on the collector ring connected to the three distributing mains 25, 26, 27 as shown. Machine 24 is connected in series with machine 23 through the commutator brushes, and from the collector ring of this machine 24 connection is made to the intermediate main 28 and the other brush bearing on the commutator of machine 24 is connected to the outside main 29 of the five wire distributing system. If machine 24 is designed for a different voltage from that of machine 23 it will be seen that the voltages between mains 27, 28 and 29 will be different from that between mains 25, 26 and 27. Such an arrangement will be desirable where a large number of different voltages are required or desirable, as in motor control for securing various speeds. For example, in Fig. 11, machine 23 is indicated as having a voltage of 100, and machine 24 as having a voltage of 150, thus giving a difference of 50 volts between mains 25 and 26 and 85 between mains 26 and 27, and a difference of 75 volts between mains 27 and 28 and between 28 and 29. An electric motor is indicated at 30 with the fields connected across the outside mains and therefore having a 85 substantially constant strength. The armature terminals are shown as provided with switches 31 and 32, the switch 31 being adapted to connect one terminal of the armature as desired to any one of the upper 100 four mains, and the switch 32 being adapted to connect the other armature terminals to any one of the lower four mains. The field strength being constant, the speed of the motor will depend upon the voltage applied to the armature. The lowest speed will be obtained by applying 50 volts to the armature which may be accomplished by connecting the armature, either between mains 25 and 26 or between mains 26 and 27. The voltage 110 may be increased and consequently increase the speed by connecting the armature by means of switches 31, 32 either between mains 27 and 28 or between 28 and 29, when a voltage of 75 volts will be applied to the armature. Next connection may be made between mains 25 and 27 when 100 volts will be applied to the armature. Connection between mains 26 and 28 will cause 125 volts to be applied to the armature. By connecting 120 between mains 27 and 29, 150 volts may be applied to the armature. Connection between mains 25 and 28 will secure an application of 175 volts to the armature terminals. If the armature terminals are connected between mains 26 and 29, 200 volts will be applied to the armature. Finally by connecting between the outside mains, the full voltage of 250 will be applied to the armature. It will thus be seen that a large number of 130

different steps or running positions are obtained which increase gradually to the maximum.

It will be understood that my invention 5 may be embodied in various forms of construction, and that I am not limited in the scope thereof to the particular forms shown and described.

Having thus described my invention, I 10 declare that what I claim as new and desire to secure by Letters Patent, is,—

1. The combination of a winding having a commutator, a multi-polar field magnet having consecutive poles of alternate polarity, 15 and a dynamo electric generating winding connected to a point of varying potential in said first named winding, said second winding having substantially one-half the conductors per circuit of said first named winding.

2. The combination of a winding having a commutator, a multi-polar field magnet having consecutive poles of alternate polarity, and a plurality of dynamo electric generating 25 windings connected to points of different and varying potentials of said first named winding, each of said plurality of windings having substantially one-half the number of conductors per circuit of said first named winding.

3. The combination of a multi-polar field magnet having consecutive poles of alternate polarity, a winding subjected to the magnetic field thereof and having a commutator and 35 brushes, and a plurality of dynamo electric generating windings connected to points of different and varying potentials of said first named winding and subjected to the same magnetic field, said plurality of windings being 40 also connected to a common point, each of said plurality of windings having substantially one-half the number of conductors per circuit of said first named winding.

4. The combination with a multi-polar direct current generator having consecutive field poles of alternate polarity, of an auxiliary winding for maintaining a fixed potential, said winding being connected at one terminal to a point in the main armature winding and having its parts located in the magnetic field to correspond substantially with the phase location of the circuit of the main winding beginning at said point of the main winding, said auxiliary winding having substantially one-half the conductors per circuit of the main winding.

5. The combination with a direct current generator, of a plurality of auxiliary windings for maintaining a fixed potential, said 60 windings having one terminal of each connected to a point in the main armature winding of varying potential and each of said windings being located in the magnetic field to correspond substantially to the phase location of the circuit of the main winding be-

ginning at the point of said main winding to which it is connected, each of said auxiliary windings having substantially one-half the conductors per circuit of the main winding and a terminal of each of said auxiliary windings being connected to a common point.

6. The combination with a multi-polar direct current generator having consecutive field poles of alternate polarity, of an auxiliary winding adapted to generate varying electromotive forces for maintaining a point of fixed potential, said auxiliary winding having its conductors located in slots of the armature core which also contain conductors of the main armature winding and the said conductors of the auxiliary winding being located at the bottom of said slots.

7. The combination with a multi-polar direct current generator having consecutive field poles of alternate polarity, of an auxiliary winding adapted to generate varying electromotive forces for maintaining a point of fixed potential, said winding being connected at one terminal to a point in the main armature winding and having its parts located in the magnetic field to correspond substantially with the phase location of the circuit of the main winding beginning at said point of the main winding and having its conductors located in the slots of the armature core which also contain conductors of the main armature winding and the said conductors of the auxiliary winding being located at the bottom of said slots.

8. In a three-wire system of electrical distribution, the combination with two main wires and a neutral wire, of a dynamo having its armature provided with a main winding connected with said main wires and an auxiliary winding having one-half as many turns as are in series between brushes in the main winding, said auxiliary winding having its ends connected with the main winding and the neutral wire.

9. In a dynamo electric machine, the combination of a multi-polar field frame having consecutive poles of alternate polarity, an armature of the direct current type, and an auxiliary winding distributed on said armature for dynamically maintaining a fixed potential between the potentials of the brushes bearing on the commutator of the armature, said winding having approximately half the conductors per circuit of the main winding, and a collector ring to which said auxiliary winding is connected.

10. In a dynamo electric machine, the combination of a multi-polar field frame having consecutive poles of alternate polarity, an armature of the direct current type, a plurality of auxiliary windings distributed on said armature for dynamically maintaining a fixed potential, said windings having one terminal of each connected to a point of varying potential in the main armature

winding, a collector ring to which one terminal of each of said auxiliary windings is connected, and each of said auxiliary windings having approximately one-half the conductors per circuit of the main winding.

11. The combination with a direct current generator, of a plurality of auxiliary windings within the influence of the magnetic field for dynamically maintaining a fixed potential, said auxiliary windings being connected to points of varying potentials in the main winding, said points of connection being displaced less than 180 degrees electrically, and each of said auxiliary windings having approximately one-half the conductors per circuit of the main armature winding.

12. In a dynamo electric machine, the combination of a multi-polar field frame having consecutive poles of alternate polarity, an armature of the direct current type, a plurality of auxiliary windings on said armature for dynamically maintaining a fixed potential between the potentials of the brushes bearing on the commutator of the armature, said auxiliary windings being connected to points of varying potentials in the main winding, said points of connection being displaced less than 180 degrees electrically, a collector ring to which one terminal of each of said auxiliary windings is connected, and each of said auxiliary windings having approximately one-half the conductors of the main armature winding.

13. The combination with a multi-polar direct current generator having consecutive poles of alternate polarity, of an auxiliary winding distributed on the armature for dynamically maintaining an intermediate fixed potential, one terminal of said auxiliary winding being connected to a plurality of points in the main winding having the same potential approximately, and a collector ring to which the other terminal of said winding is connected.

14. The combination of a multi-polar direct current generator having consecutive poles of alternate polarity, of a plurality of auxiliary windings distributed on the armature for dynamically maintaining an intermediate fixed potential, one terminal of each of said windings being connected to a plurality of points in the main armature winding having the same potential approximately, the points of connection of one auxiliary winding being displaced less than 180 degrees electrically from the points of connection to the main armature winding of another of said auxiliary windings, each of said auxiliary windings having approximately one-half the conductors per circuit of the main winding, and a collector ring to which one terminal of each of said auxiliary windings is connected.

15. The combination with a multi-polar direct current generator having consecutive poles of alternate polarity, of an auxiliary winding having approximately one-half the turns per circuit of the main winding for maintaining a fixed intermediate potential, said auxiliary winding being distributed on the armature under polar areas of the same polarity and polar areas of different polarity at the time the auxiliary winding is generating its maximum electromotive force, and a collector ring to which said auxiliary winding is connected.

16. The combination with a direct current generator, of an auxiliary winding connected to a point of varying potential in the main winding for maintaining a fixed potential, the auxiliary winding having its conductors located on the armature to correspond substantially with the phase location of conductors of the main armature winding beginning with the point in the main winding to which the auxiliary winding is connected, certain conductors of the auxiliary winding being unsymmetrically located with reference to each other, and a collector ring to which said auxiliary winding is connected.

17. The combination with a direct current generator, of a plurality of auxiliary windings for maintaining a fixed potential connected to points in the main winding, said points of connection being displaced less than 180 degrees electrically from each other, the conductors of each auxiliary winding being located on the armature in phase positions to correspond substantially with the phase location of conductors of the main armature winding beginning with the point in the main winding to which the auxiliary winding is connected, certain conductors of at least one auxiliary winding being unsymmetrically located with reference to other conductors of said auxiliary winding, and a collector ring to which said auxiliary windings are connected.

18. In a dynamo electric machine, the combination of a multi-polar field frame having consecutive poles of alternate polarity, an armature of the direct current type, a plurality of auxiliary windings on said armature for maintaining a fixed potential between the potentials of the brushes bearing on the commutator of the armature, one terminal of each of said auxiliary windings being connected to a plurality of points in the main winding having the same potential approximately, the points of connection of one auxiliary winding being displaced less than 180 degrees electrically from the points of connection to the main armature winding of another of said auxiliary windings, the conductors of said auxiliary windings being distributed so as to substantially balance the armature mechanically, the conductors of at least

one auxiliary winding being distributed on the armature under polar areas of the same polarity and polar areas of different polarity at the time the auxiliary winding is generating its maximum electromotive force and certain of the conductors of said auxiliary winding being unsymmetrically located with reference to other conductors of said winding,

and a collector ring to which said auxiliary windings are connected.

In testimony whereof I affix my signature, in presence of two witnesses.

JAMES BURKE.
